SHUTTLE

Filed Feb. 7, 1927

UNITED STATES PATENT OFFICE

LUIGI PAVIA, OF ALLENSTOWN, PENNSYLVANIA

SHUTTLE

Application filed February 7, 1927. Serial No. 166,298.

This invention relates to so-called self-threading shuttles and one object is to provide an improved tension device for shuttles and another object is to construct a shuttle so that it may be automatically threaded with certainty when the conditions are otherwise ready for that operation to occur.

In the accompanying drawing,

Fig. 1 is a plan of one end portion of a shuttle embracing the present invention;

Fig. 2 is a side elevation thereof;

Fig. 3 a section on line 3—3, Fig. 2;

Fig. 4 a plan, with the top plate 20 removed;

Fig. 5 an underneath plan view of said top plate;

Fig. 6 a section on line 6—6, Fig. 1;

Fig. 7 a front elevation of a fitting embodying certain movable parts;

Fig. 8 a rear elevation thereof; and

Figs. 9 and 10 are each a sectional view on line 9—9, Fig. 7 (the casing being omitted in Fig. 10), these views respectively showing by dotted lines the positions to which the two main parts illustrated are movable.

The shuttle includes a body 1 of generally the usual form, with a cavity 2 for the thread package 3 which may be held therein in any well known way, as so as to be automatically replaced by a fresh package when the existing one is exhausted. A channel 4 leads from the cavity toward the near (or what I term the forward) end of the body, the same communicating with a shallower longitudinal groove 5 on the top and at said end of the body and also with a deep lateral notch 6 forming a thread outlet in what I term the front side of the body—the near side in Fig. 2—which notch may be lined with a metal wear piece 6^a constituting an upwardly open eye; this may be secured in place by having its ends embedded in the main part of the shuttle body and plate 20 thereof (Fig. 2).

Channel 4 is widened between cavity 2 and groove 5 to receive the fitting shown in Figs. 7 to 9. This fitting comprises a casing 7 (which in the sense that it is fixed in the shuttle by screws 7^x or otherwise may be regarded as a part of the body) in which on axes parallel with the longitudinal axis of the shuttle

certain coacting thread-guiding means are movable and respectively supported by screws 8 and 9 tapped into the end walls of the casing respectively near the bottom and upper rear corners thereof. The first of these means includes an arbor 10 (socket-bearings of which receive the tapered ends of the screws 8), and an arm 10^a projecting into a slot in the front side of the casing and (here two) upstanding thread-guides 10^b each formed of wire and having its upper end rebent to form a hook 10^c at its rear side and terminating in an arched tail that at 10^d is inclined to form a cam surface 10^e. The normal position of this means is that shown in Figs. 9 and 10 by solid lines, its arm 10^a being held against the upper end of slot 7^a by a spring here in the form of a rubber band 11 bridging the end walls of the casing and knotted exteriorly of one, as at 11^a, Fig. 7, and having its other end engaged with an adjusting screw 12 tapped into an extension 7^b of the casing and accessible for turning (to adjust the band) from above—Fig. 4. The second of said coacting guiding means includes the pin 13 having tapered ends held in sockets in the screws 9 and a series of (here 3) thread-guides 14 extending generally horizontally across the thread-guides 10^b, their ends being received in slots 7^c; each of these guides is preferably individually movable on the fulcrum afforded by pin 13 and is here a wire bent to afford a coil-bearing 14^a and an upward salient here in the form of a beak 14^b inclined upwardly and toward the front side of the casing. The normal position of this second thread-guiding means is that shown in full lines in Figs. 9 and 10, each guide 14 being held against the stop at the upper end of slot 7^c by a spiral spring 15 arranged in a spring housing 16 of the casing and supported by an adjusting screw 17.

When on threading the shuttle the thread A is fully home it stands gripped between the guides 10^b and 14 of the two coacting thread-guiding means, which then tend to hold it zig-zag as shown at A' in Fig. 1, the thread being engaged under the beaks 14^b of the guides 14 and by the rear sides of the guides 10^b. The thread may be brought into this position in

any way by hand, as by holding a portion of it taut and causing the taut portion to bear down on the cam surfaces 10° of guides 10^b to repress them and then, after said portion has 5 passed the hooks 10^c, shifting it toward the front of the shuttle until it is engaged with the beaks 14^b.

The shuttle is constructed so that the placement of the thread in the hooks 10^c (first 10 stage) and thereupon its shifting to the front of the shuttle so that the thread is finally trapped in the position in which it is held for tension (second stage) may be accomplished not only by hand but automatically, as on a 15 backward and the then ensuing forward movement of the shuttle through the shed. Thus:

Cam surfaces 10^c form with the downwardly sloping edges 18^a of recesses 18 in the end 20 walls of casing 7 a V-shaped entrance or intake; the casing may have a wall 19 (slotted at 19^a for the guides 14) conforming to such edges as so shaped. At the opposite or front side the casing is covered by a plate 20 which 25 is held to the shuttle by screw 21 and has its inner edge curved downwardly (Fig. 6) and notched (Fig. 1) for the reception of the portions 10^a and guides 10^b. This plate has a sharpened nose 20^a overhanging the notch 6. 30 An L-shaped loop 22 (as a wire) is fixed in an upright transverse plane with the mouth of the loop open upwardly and approximately in alignment with the mentioned V-shaped entrance and its lower or offset portion directed toward and close to the thread outlet 6. Forward of this loop there may be a rearwardly inclined deflector 23 projecting downwardly from plate 20. It may be noted that the outer offset or closed end of loop 22 35 forms at 22^a a shoulder around which, after the thread, extending straight forward from the shuttle, has been engaged under the nose of plate 20, a bight may be formed as shown at A² in Fig. 1.

When the shuttle moves back through the shed the thread extends forward therefrom and is permitted by slot 5 to press downward at 10° on the guides 10^b and repress them so as to become engaged under their hooks, in 40 this operation also becoming engaged under the nose of the plate 20. On the ensuing forward movement of the shuttle the bight A² is formed around the shoulder 22^a, deflector 23 camming the thread downwardly and insuring its reaching the shoulder. Shoulder 22^a is offset transversely of the shuttle with respect to the thread supply 3 and consequently when the bight is drawn taut the taunting of the portion of the thread between the 45 shoulder and the supply and incidental lateral shifting thereof cause said portion to become trapped under the beaks 14^b as already explained.

To prevent any possibility of the thread 50 working back over the beaks in the vibrating

of the coacting thread-guiding means I may provide on the plate 20 the detents 24 alternating with the beaks as shown in Figs. 5 and 6.

The shuttle may be threaded by hand either 55 as first described herein or in a manner similar to that in which it is threaded automatically. In either case the means described acts first to catch and hold the thread when the latter is stretched toward the forward end of 60 the shuttle, clear of the shoulder, and then to exert tension on the thread when the latter is drawn into a bight around the shoulder.

Having thus fully described my invention 65 what I claim and desire to secure by Letters Patent is:—

1. A self-threading shuttle comprising, in combination, a shuttle body, a thread-guiding means therein normally urged in one direction and yieldable in the opposite direction, the 70 thread being adapted to be moved in the threading operation transversely of itself against the side of said means facing the first direction, and yieldable thread-guiding means arranged to be passed over by the 75 thread during such yielding and thereupon coactive with the first means to retain the thread in a substantially definite position for longitudinal travel, said means normally co-operating with each other when the thread 80 is in said position to maintain a bend therein.

2. A self-threading shuttle comprising, in combination, a shuttle body, a thread-guiding means therein normally urged in one direction and yieldable in the opposite direction, the 85 thread being adapted to be moved in the threading operation transversely of itself against the side of said means facing the first direction, and yieldable thread-guiding means having a beak projecting in the second 90 direction and arranged to be passed over by the thread during such yielding and thereupon coactive with the first means to retain the thread in a substantially definite position 95 in said position to maintain a bend therein.

2. A self-threading shuttle comprising, in combination, a shuttle body, a thread-guiding means therein normally urged in one direction and yieldable in the opposite direction, the 100 thread being adapted to be moved in the threading operation transversely of itself against the side of said means facing the first direction, and yieldable thread-guiding means having a beak projecting in the second 105 direction and arranged to be passed over by the thread during such yielding and thereupon coactive with the first means to retain the thread in a substantially definite position 110 in said position to maintain a bend therein.

3. A self-threading shuttle comprising, in combination, a shuttle body, a yieldable thread-guiding member therein along which the thread is slidably transversely of itself in the threading operation in one direction and having means to obstruct return sliding movement of the thread in the opposite direction, and means thereupon coactive with said 115 member to retain the thread in a substantially definite position for longitudinal travel, said means normally cooperating with each other when the thread is in said position to maintain a bend therein.

4. A self-threading shuttle comprising, in combination, a shuttle body, a yieldable thread-guiding member therein along which the thread is slidably transversely of itself 120 in the threading operation in one direction 125

and having means to obstruct return sliding movement of the thread in the opposite direction, and means thereupon coactive with said member to yieldingly resist longitudinal movement of the thread.

5. In combination, a shuttle body, and means coactive with each other to hold the filling thread zig-zag, one of said means including thread-guiding portions which are movable independently of each other toward and from the thread and separate elastic means, one for each such portion, respectively urging such portions normally against the thread.

15. 6. In combination, a shuttle body, and means coactive with each other to hold the filling thread zig-zag, one of said means including thread-guiding portions which are movable independently of each other toward and from the thread and separate elastic means, one for each such portion, respectively urging said portions normally against the thread and the other of said means being movable toward and from and normally urged against the thread.

7. In combination, a shuttle body, thread-guiding means each elastically held in a given crossing relation to the other, the thread being adapted to bear against the side of one 30 of said guiding means and to shift the same and during such shifting wipe over and into guiding engagement with the other guiding means, and both guiding means being coactive on such shifting to retain the thread in an 35 approximately definite position for longitudinal travel.

8. A shuttle having coacting means provided with surfaces arranged to form a thread-entrance for thread entered transversely of itself, one such means being yieldable to the thread from and normally urged toward the other and one of said surfaces having within such entrance means to catch and hold the thread against return through 40 said entrance, said coacting means normally cooperating with each other when the thread has been so caught to maintain a bend therein.

9. A self-threading shuttle having coacting means arranged to form a thread-entrance for 50 thread entered transversely of itself, one such means being yieldable to the thread from and normally urged toward the other and substantially closing said entrance and one having within such entrance means to catch and 55 hold the thread against return through said entrance and means, coactive with the first means on entering of the thread, to tension the thread.

10. A self-threading shuttle comprising, in 60 combination, a shuttle body having a recess therein into which thread is enterable transversely of itself, thread guiding means spanning the recess substantially at the entrance thereto and along which the thread is shift- 65 able transversely of itself, said means having

a portion adapted to catch the thread on such shifting thereof, and means to thereupon hold the thread bearing against said portion.

11. A self-threading shuttle comprising, in combination, a shuttle body having a recess 70 therein into which thread is enterable transversely of itself, thread guiding means normally held spanning the recess substantially at the entrance thereto and yieldable thereto and along which the thread is shiftable 75 transversely of itself, said means having a portion adapted to catch the thread on such shifting thereof, and means, shiftable with the thread, to hold the same pressing against the guiding means during such shifting of 80 the thread.

In testimony whereof I affix my signature.
